ENVELOPE

John J. Ormond, Boston, Mass., assignor to Art-O-Graphic Printing Company, Inc., Boston, Mass., a corporation of Massachusetts

Application July 26, 1937, Serial No. 155,587

1 Claim. (Cl. 229—68)

This invention relates to envelopes printed on the entire rear face and to a process of effecting such printing when the bottom and end flaps have been sealed down and the envelope is fully assembled.

A very considerable demand now exists in the trade for envelopes printed on the rear face with advertising matter. However, due to there having been rather widely used a poor grade of printing only partly covering the rear face of an envelope, the demand has become more selective and only when a high grade printing job such as half-tone work which effectually covers the rear face of the envelope is possible, is there a market. In addition these results must be procured at a reasonably small cost.

In the art at the present time it is very difficult to effect good printing on the rear faces or backs of envelopes and no process is known for commercially performing this operation. The reasons for such difficulty comprise the necessity of providing a "make ready" due to the uneven surface resulting from the flap portions of the envelope, the character of the envelope paper which is usually of a grade not particularly suitable for fine printing work such as half-tone prints, and the necessity for holding the envelope while it is being printed, requiring the use of grippers, with consequent unprinted areas being present on the envelope.

Of these difficulties, by far the most pertinent is the one having to do with grippers as in order to get a good print and take care of the unevennesses of the envelope surface, inks must be used which either do not dry well or which stick to the printing rolls, defeating commercial production.

By the use of a gelatine blanket transfer roll, and a particular type of printing ink, I have succeeded in eliminating the use of grippers, in effecting a process of printing adapted to commercial scale in costs, quality, and production, and in producing an envelope printed over its entire rear face characterized by several improvements from the printing which enhance the value of the envelope itself aside from its appearance.

Among the objects of my invention, there may be cited a process of printing the entire rear face of an envelope without grippers, the effecting of a waterproof and opaque covering on the back of the envelope, achieved in a substantially dry state immediately after printing, and combining printing and a sealing effect taking place along the edge formed by the folded over bottom flap of the envelope.

A further object is an envelope having advertising print disposed over the entire rear face and having its bottom flap edge substantially sealed by the printing material whereby loosening or opening up of the envelope flap is largely eliminated.

In the drawing illustrating the application of my invention:

Fig. 1 is a diagrammatic view intended to illustrate a rotary offset printing means as utilized in the carrying out of my process.

Fig. 2 is a plan view of the envelope; and

Fig. 3 is a cross section taken on the line 3—3 of Fig. 2.

While it is understood to be not new to utilize rotary offset printing machines such as that disclosed in the drawing in Fig. 1, it is again pointed out that its use in connection with the printing of the entire rear face of an envelope without grippers is new and produces a product for which there is a large demand. Overcoming the difficulties recited above is made possible by the printing equipment used in conjunction with a particular type of printing ink.

Considering first the mechanism used to effect the printing, 10 indicates a printing roll, 11 refers to a transfer roll, and 12 is a pressure roll. Roll 10 is provided with a printing plate 13 of the intaglio type in the particular case illustrated, and the roll is adapted to be rotated in the direction indicated by the arrow. This roll picks up ink from a distributing roll 14 which has been deposited thereon by an ink roll 15 diagrammatically illustrated in association with an ink trough 16 containing an ink material 17. 18 denotes a doctor blade being received in a bar 19 for removing excess ink from the printing plate 13 during rotation thereof.

According to the conventional principle of transfer printing, ink is deposited from the recessed portions of the intaglio plate 13 upon the soft resilient blanket 20 of roll 11. The latter roll rotates in conjunction with roll 12 in such a manner that a pressure member 21 engages with the blanket member 20 over which the ink impression has been delivered by roll 10.

The subject matter to be printed passes between the pressure plate 21 and blanket 20 with the impression on blanket 20 being transferred to the subject matter, after which it drops out from between the rolls.

Heretofore, considerable difficulty has been had in printing on an envelope with mechanism of this type for the reason that the folded over flap portions of the envelope create unevennesses in

the surface to be printed on, and as a result a picture or print having lighter or darker tone values is obtained. In overcoming this difficulty, the present roll 20 is provided with a blanket of 5 gelatinous material which in addition to being soft and resilient and thereby adapting itself to the uneven surface of the rear face or back of the envelope, has the character of applying the particular printing ink, about to be described, so that 10 it comes off the roll in a substantially dry state without sticking occurring. By effecting this result, the use of the grippers is entirely eliminated and therefore the entire back surface of the envelope is free to receive print and form a 15 satisfactory commercial advertising article.

As the new results occurring are effected largely by the action of the gelatine blanket with the particular ink substance described hereafter, it is not considered necessary to indicate or discuss 20 more details in the machine construction.

The material which I have found gives these new and unexpected results is a varnish mixed with metal oxides and pigments and then thinned to a point at which it will freely spread on a 25 printing plate.

While it is understood that varnishes in general have been used mixed with other ingredients such as oils, carbons and the like, to provide printing inks, it is pointed out that none of these other ingredients are present in this material, and it is 30 important to note that a mixture of dissolved gums containing pigments or oxides can be thinned to a point where it is easily applied by inking rolls to a printing plate, and when transferred from the printing plate to a gelatine 35 blanket of the character referred to and contacted with paper, will be deposited in an almost entirely dry state.

Furthermore, the bodied character of the dissolved 40 gum or varnish together with metal oxides when applied from the gelatine surface will give a uniform weight of color on a cheap grade of paper such as that of an envelope.

As an example of an ink material found to be 45 satisfactory, there may be cited a mixture of a metal oxide such as zinc oxide, incorporated with a darmer or white copal varnish made from dissolving a gum such as a batavia gum darmer in turpentine or other solvent as benzine, benzoin, 50 acetone, and the like. A mixture having the substance occurring in proportions similar to those of an enamel has been found to give very good results. The amount of thinning, for which purpose turpentine or some other suitable solvent 55 may be used, can be determined by trial and depends to some extent upon the grade and character of paper upon which the ink material is to be deposited. It has been found that with a soft 60 absorbent type of paper, a less amount of thinning may be effected, while other papers containing more sizing and having a highly glazed finish, will require an increased amount of thinner.

As a result of this particular material used, there is very pronounced waterproofing character 65 taken on by the back of the envelope, and also this type of ink gives greatly increased capacity. The waterproofing character provided by an inking material such as an enamel varnish adds greatly to the value of the envelope as an advertising medium since with the varnish applied to the entire back side of the envelope a complete protective coating is effected which is highly 70 resistant to moisture, prevents the occurrence of curling or distortion if the envelope is placed on a wet surface, protects the contents of the envelope, and is itself unaffected by moisture or other conditions during the passage through the mail which sometimes destroys the value of advertising matter on envelopes.

Since the envelope is completely covered with 5 a picture or some other ink impression, checks or other confidential data may be enclosed in the envelope without being discerned when held to the light, and such an arrangement obviates the much more expensive process of printing on the 10 inside of an envelope before it is folded for opacity 15 ity purposes.

Another important feature of the envelope and its process of printing consists in a sealing effect 15 which is produced during the printing operation. This sealing effect occurs along the edges formed by the bottom flap of the envelope being folded up. In some instances where a cheap grade of 20 paper or glue is used, and the envelope may later be subjected to moist conditions, this flap tends to open up and curl, resulting in an unsatisfactory 25 container of unsightly appearance.

In Fig. 2 there has been illustrated an envelope 24, provided with a bottom flap 25 and end flaps 26. 27 indicates printed matter on the envelope. 25 When flap 25 has been secured to end flaps 26 in the assembly of the envelope, there results an edge 28.

It has been found that the inking material is 30 of a sufficiently bodied nature as applied by the gelatine roll in proper state of dilution as to lay in against the flap edge 28 and actually provide a seal of print 27 therealong, which is very effective 35 in shutting out moisture from these glued down edges.

In all previous printing operations on envelopes, not only has there been great difficulty in applying the print to the uneven surface of the envelope, but it has been impossible to dispose the ink along the edge of the flap referred to so that 40 a white margin does not appear. The character of this type of printing ink, working in conjunction with the gelatine blanket, effectually fills in 45 ink all along the edge 28 referred to and in providing a seal along the edge, eliminates the occurrence of a white margin.

In general, the invention comprises the production of a highly useful advertising envelope whose entire rear face or back side is covered with print 50 without the use of grippers, being opaque and waterproof, and having its flap edges covered and sealed. A sufficiently even and fine grade of printing is effected as to have great commercial 55 value. These effects are made possible by using a thinned varnish which may be mixed with pigments or metal oxides and thinned to an extent where it may be applied by a gelatine roll with almost instant drying occurring and yet no sticking being present.

All of these advantages are made possible by 60 the incorporation of the blanket, the inking material, and the degree of thinning depending upon the grade of paper used. These improvements may be effected with any type of folded paper container of the envelope family where a similar 65 uneven surface is to be dealt with.

Having thus described my invention, what I claim is:

An envelope having its rear face comprising a plurality of flaps sealed together, and a closure 70 flap unsealed but overlapping the sealed flaps, the sealed flaps having a portion of an image or picture disposed or printed thereon terminating at a line which would be defined by the edge of the unsealed flap when the latter is brought into 75

its closing position, the complementary portion of the aforesaid image being disposed or printed on the surface and edge of the unsealed flap, while in its unsealed condition, whereby when the unsealed flap is brought into closed position no unprinted marginal space appears, said printed image thereby presenting substantially uniform

tonal value throughout its area and throughout each of the uneven flap portions without significant differentiation due to variation in the thickness of the body of the envelope printed upon.

JOHN J. ORMOND.
